UNITED STATES PATENT OFFICE.

PETER SCHARHAG, OF MILWAUKEE, WISCONSIN, ASSIGNOR TO SCOTT & WILLIAMS,
INCORPORATED, OF NEW YORK, N. Y., A CORPORATION OF MASSACHUSETTS.

DIAL-HARMONIZING DEVICE FOR CIRCULAR-KNITTING MACHINES.

Application filed February 24, 1927. Serial No. 170,503.

This invention relates to circular knitting machines having a dial and more particularly to means for harmonizing the vertical movements of the needle cylinder and dial. One object of the invention is to provide accurate vertical movement of the cylinder and dial together and yet at the same time obtain independent movement of the dial when the knitting elements in the dial are going into or being taken out of action. Another object of the invention is to provide means of the character described which permit accurate adjustment of the space between the dial and the cylinder and further to provide means giving movements of uniformly different lengths to the dial and cylinder respectively. In the well-known Scott & Williams type of circular hosiery knitting machines, of which an example is illustrated in the patent to Robert W. Scott No. 1,152,850 dated September 7, 1915, a change in stitch length is brought about by a vertical adjustment of the needle cylinder effected primarily from the main pattern drum. This adjustment of the needle cylinder was accomplished through the medium of a lever acting upon the cylinder raising tube through which the knitted fabric passes down from the knitting, the needle cylinder being operated vertically by this cylinder raising tube. In order to keep the correct stitch length on a circular rib knitting machine having a dial, it is necessary that the relative positions of the dial and needle cylinder be accurately maintained. It is also necessary to provide sufficient space for manipulations of the yarns and fabric when forming a heel or toe pocket by lifting the dial away from the needle cylinder temporarily. All the vertical adjustments of the dial have heretofore been obtained directly from shafts rotating with the main pattern drum, but this arrangement is not sufficiently accurate and the present invention is an improvement thereon. The invention includes unitary means causing uniform vertical movement of the cylinder and dial at certain times and causing independent vertical movement of the dial at other times.

In the accompanying drawings, I have shown my invention applied to the well-known Scott & Williams type of hosiery knitting machine, but it should be understood that the invention can be applied to other types of circular knitting machines.

Fig. 1 is a side elevation of a portion of a Scott & Williams seamless hosiery rib knitting machine showing one embodiment of the new dial harmonizing device; 55

Fig. 2 is a detail elevation of the harmonizing means taken on the line 2—2 of Fig. 1; 60

Fig. 3 is a side elevation of portions of the machine showing a preferred embodiment of the invention;

Fig. 4 is a rear elevation of the dial and its associated parts taken on the line 4—4 of Fig. 3; 65

Fig. 5 is a rear elevation of the operating lever and dial raising bracket taken on the line 5—5 of Fig. 3; while

Fig. 6 is a detail elevation of the dial raising bracket viewed from the left of the machine on the line 6—6 of Fig. 5. 70

In these views the bedplate B carries the rotating needle cylinder 260. There is the usual cylinder raising tube 280 guided at its upper end in a pendant flange 259 on the under side of the bedplate B, and vertically adjustable therein in order to impart vertical movement to the needle cylinder as described in the above-mentioned patent to Robert W. Scott No. 1,152,850. There is the usual main pattern drum 120 on the shaft 76. 80

Referring now to the embodiment of my invention found in Figs. 1 and 2 of the drawings, it will be noted that the dial D is mounted on a spindle d, which spindle is splined at g⁵ to slide through and rotate with the gear g'. The dial is supported by a bracket 15 bolted on a latch ring 550 which in turn is pivoted to the bracket 401 (Fig. 5). 90

The dial is adapted to be moved vertically with respect to the latch ring 550 and the dial bracket 15 by mechanism which will now be described. On the upper end of the dial spindle d is a non-rotating yoke d¹⁴. The dial gears are covered by a casing 16 fastened to the bracket 15. In this gear casing 16 is a fore-and-aft slot 130 in which lies a lever 128, with a pivot point near the front of the machine at 129. The free end of the lever 128 extends rearwardly beyond the casing 16. Held in position by the yoke d¹⁴ is an arm d¹³ and passing through this arm is a downwardly extending adjustment screw d¹⁶ lying above the lever 128 at a little distance 100 from its pivot point 129. These parts are so arranged that a raising and lowering of the rearwardly extending free end of the lever 105

128 will cause the dial to be raised and lowered without affecting the engagement between the gears g^2 and g^1 .

The rear end of this lever 128 overlies a plate 127 on the upper end of a thrust rod 460 which passes downwardly to the main pattern drum 120 on which are located the cams 501 to raise and lower the dial when rib knitting is stopped and begun.

10 For the purpose of raising and lowering the dial in unison with the needle cylinder when knitting rib fabric in which changes of stitch length are desired, unitary lever means are provided having a fulcrum on a stationary part of the machine but controlled from a bracket on the cylinder raising tube. In the example shown in Figs. 1 and 2, there is an operating lever 191 linked at one end to the thrust rod 460 and pivoted at the other 15 end to a bearing 192 on the bedplate. When the thrust rod is in its lowermost position, this link lies in a slot in the upturned end of a bracket 193 rigidly mounted on the cylinder raising tube 280, the extent to which the 20 link descends into the slot being determined by an adjusting screw 194. When the thrust rod rides off the cams 501 on the main pattern drum 120, the link rests upon its adjusting screw and consequently the dial will be 25 raised and lowered in unison with the cylinder raising tube. The space between the middle cylinder and the dial can be adjusted by means of this screw 194 and by changing the distances between the fulcrum and this adjusting screw the space between the cylinder 30 and dial can be varied according to the height of the cylinder, i. e., the length of stitch.

In Figs. 3, 4 and 5 a preferred embodiment of the invention is shewn in which lever 191 is replaced by an operating lever 272 pivoted to the main frame of the machine at 40 273. This lever extends both rearwardly and forwardly from its pivot point, the rearward extension being connected to a special thrust rod 125 whose upper end carries a slotted adjusting plate 127. In the slot of this adjusting plate plays the tapered end of the dial raising lever 128' which latter is pivoted at 45 129 to the dial gear casing 16 as before. This rearwardly extending portion of the operating lever 272 has a foot 272' acting as a stop against the frame of the machine to prevent the thrust rod 125 from dropping too far. The forward extension of the lever 272 is 50 availed of when it is desired to move the dial independently of the needle cylinder by so locating this forward extension that it is acted upon by a disc cam 288 on the pattern chain shaft rotating in unison with the main pattern drum by means of the gears 122, 123, 121. For raising and lowering the dial in 55 unison with the needle cylinder there is a dial raising bracket 274 fastened to the cylinder raising tube 280, which extends to a point just to the rear of the pivot point of the op-

erating lever 272. There is a vertical holding piece 275 pivoted on the end of the dial raising bracket at 279, containing an adjustment screw 276. This adjustment screw is adapted to engage the under side of a horizontal plate 277 on the operating lever, the point of engagement of the adjustment screw being between the pivot point of the operating lever 272 and the connection between the lever and the thrust rod 125. It will be obvious that when the cylinder raising tube 280 rises the dial will also rise and that by varying the adjustment screw 276 the distance between the dial and cylinder can be varied. In case it is desirable to vary the distance between the dial and the needle cylinder automatically in proportion to the elevation of the needle cylinder, the point of contact between the adjustment screw 276 and the plate 277 can be varied by rocking the holding piece 275 about its pivot center 279. This rocking can be accomplished by means of said screws 278 engaging the holding piece 275 from the sides (Fig. 6).

It will be obvious from the description which has already been given that whenever the knitting instruments in the dial are idle or it is desired to lift the dial out of the way of the needle cylinder and the fabric which is being formed thereon, the cams 501 on the main pattern drum—or the disc cam revolving in unison with the main pattern drum as the case may be—will cause the dial to be lifted out of the way, and that when it is desired to have the dial and needle cylinder move simultaneously in accurately maintained relation, the operating lever pivoted to a stationary part of the machine acting under the influence of the cylinder raising tube will accomplish the desired movement.

What I claim is:

1. A circular knitting machine having a needle cylinder and a dial, in combination with unitary means adapted to raise said cylinder and to raise said dial through movement of said cylinder and in unison therewith.

2. A circular knitting machine having a needle cylinder and a dial, in combination with unitary means adapted to raise said cylinder and to raise said dial through movement of said cylinder and in unison therewith and means to cause independent raising of the dial.

3. A circular knitting machine having a pattern drum, a needle cylinder, means adapted to raise and lower said needle cylinder, and a dial, in combination with unitary means adapted to raise and lower said dial under the control of the pattern drum or of the needle cylinder raising means.

4. A circular knitting machine having rotating pattern means, a needle cylinder, means adapted to raise and lower said needle cylinder, a dial and a thrust rod actuated by

said rotating pattern means to raise and lower said dial, in combination with means including a lever connected to said thrust rod and to a stationary portion of the machine 5 adapted to raise said thrust rod when the needle cylinder is raised.

5. A circular knitting machine having a needle cylinder, a cylinder raising tube, a dial and a thrust rod adapted to raise said 10 dial, in combination with cam means adapted to raise said thrust rod and means actuated by the cylinder raising tube also to actuate said thrust rod.

6. A circular knitting machine having a 15 pattern drum, a needle cylinder, a dial and a thrust rod to raise said dial actuated by said pattern drum, in combination with cam means operated in unison with the pattern drum, means moving in unison with the 20 needle cylinder to raise the latter, a pivoted lever adapted to be actuated by said cam means and by said means moving in unison with the needle cylinder to actuate said thrust rod.

25 7. A circular knitting machine having a needle cylinder, a dial and a thrust rod adapted to raise and lower said dial, in combination with cam means adapted to raise and lower said thrust rod and independent means 30 operated in unison with the needle cylinder

adapted to raise and lower said thrust rod when said cam means have not raised the latter.

8. A circular knitting machine having a needle cylinder, a cylinder raising tube, a dial and a thrust rod to raise and lower said dial, in combination with cam means operated in unison with the pattern drum, and an operating lever for said thrust rod adapted to be actuated by said cylinder raising tube or by said means moving in unison with the pattern drum. 35 40

9. A circular knitting machine having rotating pattern means, a needle cylinder, a cylinder raising tube, a dial and a thrust rod actuated by said rotating pattern means to raise and lower said dial in combination with an operating lever pivoted on a stationary portion of the machine adapted to raise and lower said thrust rod, cam means operated in unison with said pattern drum adapted to actuate said operating lever and bracket means on said cylinder raising tube adapted to move said operating lever an adjustable amount with relation to the movement of said cylinder raising tube. 45 50 55

In testimony whereof I have signed my name to this specification.

PETER SCHARHAG.
